UNITED STATES PATENT OFFICE.

A. IRVING GRIGGS, OF NEW YORK, N. Y.

DESIGN FOR THE ORNAMENTATION OF SHEET METAL.

SPECIFICATION forming part of Design No. 18,391, dated June 19, 1888.

Application filed May 7, 1888. Serial No. 273,137. Term of patent 14 years.

To all whom it may concern:

Be it known that I, A. IRVING GRIGGS, a citizen of the United States, and a resident of New York city, in the county and State of New York, have invented and produced a new and original Design for the Ornamentation of Metal, of which the following is a full, clear, and exact description.

My design is intended for the ornamentation of sheet metal; and it consists of representations of sprays of raised flowers and leaves arranged in irregular and unstudied order upon the surface, the spaces between the several detached sprays being filled or studded with small raised stars, also arranged in irregular and unstudied order.

In the accompanying drawing, which represents a piece or fragment of sheet metal ornamented with my design, *aa* are patterns, in relief, of sprays of flowers and leaves, each spray being composed of a flower and leaves and being detached from the others, and said sprays being scattered or distributed in an irregular manner over the entire surface, as shown. The spaces between the sprays *a* are filled or studded with raised stars *b*, arranged, also, in an irregular manner.

In saying that the several sprays of flowers and leaves and the intermediate stars are arranged in an irregular manner I mean that they are not arranged in lines or rows and equally spaced, and that there is no obvious recurrence of the same spray on the same line at regular distances apart.

The several sprays *aa* are somewhat conventionalized representations of daisies and similar flowers.

Having thus described my design, I claim-- The herein described design for the ornamentation of sheet metal, which consists of the raised patterns of flowers and leaves arranged upon the surface in detached sprays *aa*, placed in irregular and unstudied order, and the intervening raised stars *b b*, arranged in irregular and unstudied order on the surface between said sprays *aa*, as shown.

In witness whereof I have hereunto signed my name in the presence of two subscribing witnesses

A. IRVING GRIGGS.

Witnesses:

HENRY CONNETT,
J. D. CAPLINGER.
